CLAIM

The ornamental design for a gaming surface graphic for an electronic display, as shown and described.

DESCRIPTION

A portion of the disclosure of this patent document contains material which is subject to copyright protection. The copyright owner has no objection to the facsimile reproduction by anyone of the patent document or patent disclosure, as it appears in the Patent and Trademark Office patent file or records, but otherwise reserves all copyright rights whatsoever.

FIG. 1 illustrates an electronic display with a gaming surface graphic in plan view.

FIG. 2 illustrates in greater detail a central portion of the gaming surface graphic of FIG. 1; and,

FIG. 3 illustrates in perspective an electronic display with the gaming surface graphic of FIG. 1.

The dash-dot-dot-dash broken lines represent the boundaries of the claimed design. The evenly spaced broken lines showing of an electronic display are included for the purpose of illustrating portions of an "article" and forms no part of the claimed design.
